(57) **CLAIM**

The ornamental design for handheld electronic communication device, as shown and described.

DESCRIPTION

FIG. 1 shows a front perspective view of the handheld electronic communication device in a closed configuration;

FIG. 2 shows a front elevational view thereof;

FIG. 3 illustrates a rear elevational view thereof;

FIG. 4 illustrates a right side elevational view thereof;

FIG. 5 illustrates a left side elevational view thereof;

FIG. 6 illustrates a top plan view thereof;

FIG. 7 illustrates a bottom plan view thereof;

FIG. 8 illustrates a front perspective view of the handheld electronic communication device in an operating configuration;

FIG. 9 illustrates a rear elevational view thereof;

FIG. 10 illustrates a front elevational view thereof;

FIG. 11 illustrates a right side elevational view thereof;

FIG. 12 illustrates a left side elevational view thereof;

FIG. 13 illustrates an upper rear elevational view thereof; and,

FIG. 14 illustrates a bottom rear elevational view thereof.

The broken lines shown throughout the views that are immediately adjacent to the shaded areas and define unshaded regions, represent the bounds of the claimed design, while all other broken lines are directed to environment and are for illustrative purposes only; the broken lines form no part of the claimed design.
